UNITED STATES PATENT OFFICE.

DAVID F. HAYNES, OF BALTIMORE, MARYLAND.

DESIGN FOR A EWER OR JUG.

SPECIFICATION forming part of Design No. 24,183, dated April 9, 1895.

Application filed March 13, 1895. Serial No. 541,625. Term of patent 3½ years.

To all whom it may concern:

Be it known that I, DAVID F. HAYNES, a citizen of the United States, residing at Baltimore, Maryland, have invented and produced 5 a new and original Design for a Ewer or Jug, of which the following is a specification, reference being had to the accompanying drawing, forming a part hereof.

The drawing forming a part hereof is a perspective side elevation of the ewer.

I describe this ewer or jug as follows: The body A is a frustum of a spheroid with the smaller end forming the bottom. Near the bottom is a band B with beaded edges and 15 rosettes between the beads. The remainder of the body is plain.

At the top of the body A is a molded collar C, and from this collar springs the neck D. The neck flares outwardly and the flare at the 20 front is greater than at the rear or sides, so as to form a lip a. The upper edge of the

neck is of irregular outline and at the sides it drops considerably and is formed by two curves which meet in a dull point b which is not greatly elevated above the lowest portion 25 of the curves. The edge of the neck is beaded so as to present a well defined line.

The exterior of the neck is decorated with a graceful design composed of leaves and interlaced scrolls in relief.

The handle E connects the neck at a point 30 below the beaded edge with the portion of the body having the greatest diameter, and it is decorated with scrolls and leaves.

I claim as my invention—

The design for a ewer or jug, herein shown and described.

DAVID F. HAYNES.
